UNITED STATES PATENT OFFICE.

HENRY A. WEIHMANN, OF PHILADELPHIA, PENNSYLVANIA, ASSIGNOR TO
SIMONS, BROTHER & CO., OF SAME PLACE.

DESIGN FOR A CANE OR UMBRELLA HANDLE.

SPECIFICATION forming part of Design No. 19,992, dated July 1, 1890.

Application filed April 15, 1890. Serial No. 348,086. Term of patent 3½ years.

To all whom it may concern:

Be it known that I, HENRY A. WEIHMANN, a citizen of the United States, residing in Philadelphia, in the county of Philadelphia and State of Pennsylvania, have invented and produced a new and original Design for Cane or Umbrella Handles, of which the following is a specification, reference being had to the accompanying drawing, forming part thereof.

10 In the drawing is shown a side elevation of a cane or umbrella handle illustrating my new design.

A is the body part, and is made long and very gradually increases in diameter from bottom upward, and terminates at the top in the loop B, having the spiral end C resting against the upper end of the body part. The body part A is encircled by spiral ribs D of plain surface and interposed spirals E of ornamenta-

tion. The upper ends of the spirals D and E 20 disappear in the loop B, leaving the greater portion of said loop of plain or shaded surface. The lower part of the handle is finished by an annular band F of ornamentation and two annular bands G of plain surface.

25 The handle is made of any suitable material.

Having now described my new design, what I claim as new, and desire to secure by Letters Patent, is—

30 The design for cane or umbrella handles, substantially as herein described and shown.

In testimony of which invention I have hereunto set my hand.

HENRY A. WEIHMANN.
